UNITED STATES PATENT OFFICE.

JAMES W. IVORY, OF PHILADELPHIA, PENNSYLVANIA.

MOUTHPIECE FOR CIGARS.

1,121,253.

Specification of Letters Patent. Patented Dec. 15, 1914.

Application filed December 11, 1913. Serial No. 805,910.

To all whom it may concern:

Be it known that I, JAMES W. IVORY, a subject of the King of Great Britain, residing in the city and county of Philadelphia, 5 State of Pennsylvania, have invented a new and useful Mouthpiece for Cigars, of which the following is a specification.

My invention consists of a mouth piece for a cigar which is composed of a pair of 10 jaws adapted to be connected with the tip end of the cigar and serve to prevent direct contact of the teeth of the smoker with the same, while in a measure, allowing the lips to close around said tip to preserve the draft 15 in the cigar while being smoked.

The invention is satisfactorily illustrated in the accompanying drawing, but the important instrumentalities thereof may be varied, and so it is to be understood that the 20 invention is not limited to the specific details shown and described.

Figure 1 represents a perspective view of a mouth piece for a cigar embodying my invention. Fig. 2 represents a side elevation 25 thereof. Fig. 3 represents a rear end view thereof. Fig. 4 represents a longitudinal section thereof on line $x-x$, Fig. 1. Figs. 5, 6, 7 and 8 represent perspective views and an elevation respectively of other embodiments of the invention.

Similar numerals of reference indicate corresponding parts in the figures.

Referring to the drawings:—1 designates the mouth piece which is formed of jaws 2 and 3, each of which is provided at or about their rear ends with ears 4, in which is inserted and secured the pintle 5 which forms the axis of the jaws and permits the latter to be opened and closed at their forward 40 ends. The inner faces of said jaws are curved to conform to the contour of the tip end portion of a cigar so as to properly and nicely embrace the same, avoiding rotation of the cigar in the piece or vice-versa. On 45 said pintle is the coil spring 6, whose ends bear respectively in opposite directions against the heel ends of said jaws 2 and 3, so as to exert closing pressure on the latter, and cause them to take firm hold on a cigar 50 when applied thereto, as shown in Figs. 1 and 4. On the inner sides of the jaws are the spurs or prongs 7 which are adapted to pierce the cigar and so prevent longitudinal and lateral displacement of the jaws therefrom. The sides of the jaws are cut away 55 forming the inwardly-extending recesses 8 at said sides and so uncover the relative portions of the cigar while the other portions of the latter are covered by the main lengths of the jaws. The rear terminals of the jaws 60 are somewhat flaring and so the portions of the jaws forward of said terminals are somewhat depressed, the depressions being anterior to the fastening pivots 5.

It will be noticed that the rear end of 65 the mouth piece is open due to the separation of the jaws at said end, so that the smoker can draw through the same and so draw from the adjacent end of the cigar, the latter as usual in smoking. 70

The operation is as follows:—The front of the jaws are opened by pressure on the rear thereof, and the tip end of a cigar inserted between the jaws. The jaws are then allowed to close on the cigar when the spurs 75 7 pierce the latter, it being evident that the spring 6 presses the jaws in their set position upon the cigar and holds them thereat, preventing improper opening of the same, while the said spurs 7 prevent shifting of 80 the jaws from the cigar in longitudinal, lateral or rotary direction thereof. The device with the cigar partly covered and embraced by the jaws 2 and 3 may now be inserted in the mouth when the teeth of the smoker 85 will contact with and press against the depressed portions of said jaws and thus be removed from direct and injurious contact with the tobacco, while the lips may close around the jaws and the side of the cigar 90 at the recesses 8, so that the tip end of the cigar will be sufficiently enveloped by the lips to effect the draft on the cigar by the mouth through the open end of the jaws and the tip end of the cigar, said end being cut 95 as usual. When the rear ends of the jaws are pressed together the front ends of the same will open, and so separate from the cigar, the spurs 7 then emerging from the cigar, and so the device is removed from its 100 operative position ready for further use on another cigar. The outer contour of the jaws is somewhat curved so as to conform to the lips of the smoker and prevent the same from slipping forwardly thereon, and 105 while they may be pressed by the lips the teeth of the smoker may also assist in closing the jaws and cause the device to retain a firm hold on the cigar it being noticed that the flaring rear terminals prevent the teeth 110 from slipping rearwardly over the same, the device thus being adapted to be held steadily.

in position in the mouth between the teeth and lips.

In Fig. 5, the jaws 2 and 3 are integral, they being connected at their rear ends by 5 the plate 9 in which is a perforation 10 for drawing the smoke therethrough, said jaws having a certain resiliency for closing purposes, but being adapted to be pressed by the lips and teeth of the smoker, so as to 10 properly envelop the portion of the cigar that they surround, and be firmly clamped upon said portion.

In Figs. 6 and 7, the jaws have rearward extensions 11 in which are draft perforations 15 or holes 12, the extensions in Fig. 6 being of the form of knuckles 13 through which the pinte 14 is past as the axis of the jaws. In Fig. 7, the sides 15 of the rear portions of the jaws overlap so as to move 20 one on the other in the closing and opening of the jaws, said sides having connected with them the axial pinte 16 of the jaws, the results of operation, however, in said Figs. 5, 6, and 7 being similar to that in 25 Figs. 1, 2, 3 and 4.

In Fig. 8, the heel ends of the jaws are of the form of tongues 17 which are adapted to be fitted to each other by sliding one on the other and so interlock, thus connecting 30 said ends and consequently the jaws, allowing the latter to be somewhat resilient, and close and open, and thus be operative as in the previous constructions.

Having thus described my invention what 35 I claim as new and desire to secure by Letters Patent, is:—

1. A mouth piece for a cigar composed of 40 jaws, the inner faces whereof are adapted to conform to the contour of the tip end portion of a cigar, and means for connecting the rear portions of said jaws, the portion 45 of the jaws anterior of their connection being depressed forming seats for the teeth of the smoker to press said jaws tightly on the cigar.

2. A mouth piece for a cigar composed of 50 jaws, the inner faces whereof are adapted to conform to the contour of the tip end portion of the cigar, means for connecting the rear portions of said jaws, and flaring walls on the rear of the jaws, the portion 55 of the jaws anterior of their connection being depressed for seating the teeth of the

smoker thereon to press the jaws tightly on the cigar, said flaring walls being adapted 55 to prevent rearward slipping of the teeth from the device.

3. A mouth piece for a cigar composed of jaws, the inner faces of which are adapted to conform to the tip end portion of the cigar, 60 a connection for said jaws, and means for closing said jaws on the cigar, the sides of said jaws anterior to their places of connection being cut away adapting the lips of the smoker to embrace the exposed portion 65 of the tobacco at said cut-away sides, while the rear portions of the jaws are in the mouth.

4. A mouth piece for a cigar composed of jaws, the inner faces of which are adapted 70 to conform to the contour of the tip end portion of a cigar, means for connecting said jaws, the rear portions of said jaws being adapted to be inserted in the mouth of the smoker, and the portion intermediate of 75 said rear portions and the jaws proper being depressed adapting it to be engaged by the lips and teeth of the smoker to press said jaws proper against the cigar.

5. A mouth piece for a cigar composed of 80 jaws, the inner faces whereof are adapted to conform to the contour of the tip end portion of a cigar, and means for connecting the rear portion of said jaws, the portion of the 85 jaws anterior of their connection being depressed forming seats for the teeth of the smoker to press said jaws tightly on the cigar, the inner face of a jaw having a piercing point connected firmly therewith.

6. A mouth piece for a cigar composed of 90 jaws, the inner faces of which are adapted to conform to the contour of the tip end portion of a cigar, a connection for said jaws, and a depression of the jaw portions of the 95 jaws anterior to the places of said connection adapted to be engaged by the teeth of the smoker to press the jaws on the cigar, the sides of the jaws adjacent to their places of connection being cut away adapting the lips of the smoker to embrace the exposed 100 portion of the tobacco, while the rear portions of the jaws are in the mouth.
